UNITED STATES PATENT OFFICE.

OTIS E. ZIPPERER, OF COLEMAN, FLORIDA.

RAILROAD SWITCH.

Application filed July 13, 1925. Serial No. 43,352.

To all whom it may concern:

Be it known that I, OTIS E. ZIPPERER, a citizen of the United States, residing at Coleman, in the county of Sumter and State 5 of Florida, have invented certain new and useful Improvements in Railroad Switches, of which the following is a specification.

This invention relates to switches for railroads provided with means for locking 10 the points in position when the main line is open; and it consists in the novel construction and combination of the parts hereinafter fully described and claimed.

In the drawings, Figure 1 is a plan view 15 of a railroad switch provided with means for locking the points according to this invention. Fig. 2 is a plan view of the slideable tip lock showing it retracted and the rail in section. Fig. 3 is a cross-section, 20 taken on the line 3-3 in Fig. 1, and showing the operating devices for the points. Fig. 4 is a cross-section, taken on the line 25 4-4 in Fig. 1, and showing the disk clamps and their operating devices. Fig. 5 is a side view of the stand, looking from the left in Fig. 1. Fig. 6 is a side view of one of the eccentric locking disks, and the tip lock.

The rails 8 of the main line, and the rails 30 9 of the side track are spiked in place in the usual way, and 10 are the pivoted points which connect the side track with the main line. These two points have a coupling bar 12 arranged crosswise of them and permanently 35 secured to them. Two sills 14 are arranged under the rails and points, and are similar to the usual ties when extended upon one side of the track.

A locking shaft 15 is journaled in bearings 16 secured to one of the sills, and projects under one rail and one point. Two eccentric locking disks 17 are secured on this shaft, and straddle the said rail and point when the main line is open so that the 40 points are locked. A locking block 18 is arranged to slide longitudinally upon the lower parts of the rail, and has a beveled tooth 19 on one side which overlaps the tip of the point and locks it to the rail when 45 the main line is open.

This block is operated from the locking shaft 15 by means of a crank and a connecting-rod 20. The connecting-rod 20 is preferably formed of two parts having right and left screwthreaded end portions 21 connected by a turnbuckle 22 so that its length 50

may be varied and adjusted. One end of the connecting rod 20 is pivoted to the locking block 18 by a pin 25, and its other end is connected to a crank-pin 26 which projects from one of the eccentric disks 17, but any other approved form of crank can be used when the two eccentric disks are not provided. A spring 27 encircles the locking shaft 15. One end of this spring engages 60 with a projection 28 on the shaft, and its other end has an arm 29 secured to the sill, and this spring normally holds the disks and block in the locked position. A lever 30 is secured to the locking shaft, and may be 65 operated by hand or by foot to rock the shaft 15 and release the points.

When the points are released they are slid pivotally to the closed position by 70 means of the coupling-bar 12 and any suitable points operating mechanism connected to it. One means for operating the coupling-bar and the locking shaft simultaneously is a hand lever 32 pivoted by a pin 33 to lugs 34 on a plate 35. This plate 35 is 75 secured on a vertical shaft 36 which is journaled in a stand 37, and the pivot pin 33 is arranged to one side of the vertical shaft. A crank-plate 38 is secured on the lower 80 part of the vertical shaft 36, and is provided with a radial slot 37' and an adjustable crank-pin 38' secured in the slot.

The crank-pin 38' is connected with the coupling-bar 12 by a connecting-rod 39, and the throw of the crank-pin 38' is adjusted 85 in the slot so as to give the requisite amount of movement to the points.

A push-rod 40 is arranged to slide vertically in guide holes in the stand 37, and the upper end portion of this rod projects 90 through a notch 41 in the plate 35 on the other side of its axis from the pivot of the hand lever, and thereby normally locks the plate to the stand. The locking shaft 15 has an arm 42 secured on it, and 43 is a 95 connecting-rod between the arm 42 and the push-rod 40. A spring 44 is arranged around the push-rod to raise it, and may be used instead of the spring 27 to hold the points locked, or both springs can be used. 100

The hand lever 32 has a cranked end portion 45 for engaging with the upper end of the push-rod and its notch 41. When the lever 32 is not in use it engages with a notch 46 in the edge of the stand, and also locks 110 the plate 35 to the stand.

When the hand lever 32 is raised, its

cranked end pushes the push-rod out of the notch in the plate, and take its place in the notch. The push-rod releases the points when thus pushed down, and the points can then be closed by turning the vertical shaft 36 on its axis by means of the hand lever 32. The points can be held in the closed position if desired by means of a catch or latch 48 on the connecting-rod 39 which can be moved so as to engage with a stationary projection 49 and prevent the return movement of the points to the open position. The points and their locking devices can also be operated in other ways besides those described, and they can be operated by means of electricity or compressed air.

When the points are locked as hereinbefore described many very serious accidents are prevented, as the points are locked directly to the rails, and remain locked if any accident to or breakage of their operating devices takes place.

What I claim is:

- 25 1. The combination, with a stationary rail, and a movable point; of a slideable block for locking the tip of the point to the rail, a locking shaft journaled crosswise of the rail and point, eccentric locking disks secured on the said shaft and straddling the said point and rail when in the locked position, and a connecting-rod arranged between one of the said eccentric disks and the said slideable block.
- 30 2. The combination, with a stationary rail, and a movable point; of a locking block slideable longitudinally on the lower part of the rail and having a tooth on one side which normally overlaps the tip of the point, a locking shaft journaled crosswise of and projecting under the rail and point, eccentric locking disks secured on the said shaft and normally arranged to lock the point to the rail, and a connecting-rod pivot-

ed to one of the disks and to the said locking block on the other side of the rail from the said tooth.

3. The combination, with a stationary rail, and a movable point; of a locking shaft mounted crosswise of the rail and point, a locking device for the rail and point operatively connected with the locking shaft, a stationary stand, a vertical shaft journaled in the stand and having a crank on its lower end, a connecting-rod operating the point from the said crank, a plate secured on the upper part of the vertical shaft and provided with a notch on one side, a vertical push-rod slideable in the stand and in the said notch, an arm secured on the said locking shaft, a connecting-rod between the said arm and the push-rod, and a hand lever pivoted to the other side of the said plate from its notch and provided with a cranked end portion for pushing the push-rod downwardly in the notch and taking its place therein so as to enable the hand lever to be used to revolve the plate and operate the movable point.

4. A combination of parts as set forth in claim 3, and having also a spring which normally holds the push-rod in the notch of the said plate with the locking device in engagement with the rail and point.

5. A combination of parts as set forth in claim 3, the said stand being provided with a notch with which the said hand lever engages automatically when the push-rod is raised.

6. A combination of parts as set forth in claim 3, the crank on the lower end of the said vertical shaft being provided with a radially adjustable crank-pin to vary the extent of movement of the said point.

In testimony whereof I have affixed my signature.

OTIS E. ZIPPERER.
